(57) **CLAIM**

The ornamental design for a reversible pet harness as shown and described.

DESCRIPTION

FIG. 1 is a front perspective view of a reversible pet harness showing our new design in a condition of use in a first configuration;

FIG. 2 is a front perspective view thereof;

FIG. 3 is a rear perspective view thereof;

FIG. 4 is a front elevational view thereof;

FIG. 5 is a rear elevational view thereof;

FIG. 6 is a right-side elevational view thereof;

FIG. 7 is a left-side elevational view thereof;

FIG. 8 is a top plan view thereof;

FIG. 9 is a bottom plan view thereof;

FIG. 10 is a front perspective view of the reversible pet harness of FIG. 1 shown in a condition of use in a second configuration inverted from the first configuration;

FIG. 11 is a front perspective view thereof;

FIG. 12 is a rear perspective view thereof;

FIG. 13 is a front elevational view thereof;

FIG. 14 is a rear elevational view thereof;

FIG. 15 is a right-side elevational view thereof;

FIG. 16 is a left-side elevational view thereof;

FIG. 17 is a top plan view thereof; and,

FIG. 18 is a bottom plan view thereof.

The stippling represents portions of the reversible pet harness having a contrasting appearance with the line shading portions. The longer equally spaced broken lines on the reversible pet harness depict portions of the reversible pet harness that form no part of the claimed design. The shorter equally spaced broken lines on the reversible pet harness depict stitching that forms no part of the claimed design. In FIGS. 1 and 10, the longer equally spaced broken lines
